UNITED STATES PATENT OFFICE.

EUGENE G. KERLIN, OF SALEM, VIRGINIA, ASSIGNOR TO COMAS CIGARETTE MACHINE COMPANY, OF SALEM, VIRGINIA, A CORPORATION OF VIRGINIA.

PASTING DEVICE FOR PACKAGING MACHINES.

Application filed August 25, 1922. Serial No. 584,290.

To all whom it may concern:

Be it known that I, EUGENE G. KERLIN, a citizen of the United States, residing at Salem, in the county of Roanoke and State of Virginia, have invented certain new and useful Improvements in Pasting Devices for Packaging Machines, of which the following is a specification.

This invention relates to pasting devices for packaging machines.

The object of the invention is to apply to the outside wrapper along the longitudinal edges thereof a strip of glue, whereby the outside wrapper when folded around the package is held in place.

A further object is to apply glue to the outside wrapper in such a manner that when it is folded around the foil covering which has been previously folded it will stick to the foil covering and hold the two wrappers together.

A further object of the invention is to provide means whereby the strips of paper are passed through the pasting machine at predetermined intervals.

In the accompanying drawings:

Fig. 1 is a side elevation of the pasting device;

Fig. 2 is a top plan view thereof;

Fig. 3 is a diagrammatic view showing the relative position of the actuating cams.

The numeral 1 indicates a bracket extending horizontally from the base, and suspended therebeneath is a glue-pot 2, the latter being provided with a lug 3 through which passes a thumb-screw 4, the threaded end of which is received in the bracket 1, forming a means for detachably securing the glue-pot 2 in place. Intermediate of the bracket 1 is a transverse bearing 5 adapted to support a shaft 6 upon which is keyed a pair of delivery rollers 7, 7, of such a diameter as to enter the glue-pot 2, said shaft being rotated by a pulley 8. Arranged at the rear of the glue-pot are horizontally arranged scrapers 9—9 provided at the outer ends with open slots 10 and adjustably held in place by screws 11, the inner ends thereof contacting with the rollers 7—7 serving as scrapers, whereby the delivery of the glue is controlled.

At the base of the bracket 1 is pivoted a shaft 12 carrying rocker-arms 13—13, and rotatably mounted at the upper ends there-

of is a transverse shaft 14 having secured thereto a pair of transfer-disks 15—15.

The numeral 16 indicates a frame having projecting lugs 17 forming bearings for the transverse shaft 18 upon which are mounted rocker-arms 19—19 adapted to support at 60 their upper ends a transverse shaft 20. Mounted upon the shaft 20 are a set of peripherally grooved guide or backing rollers 21—21. These rollers, together with the transfer-disks 15—15 and the delivery 65 rollers are all aligned.

The wrappers 22 are fed downwardly through a chute 23, said chute being provided with vertical guide-walls 24—24 arranged outside of the rollers 21—21, the 70 wrappers passing between the rollers 21—21 and the transfer rollers 15—15, the roller 21—21 acting as a backing for the paper as the transfer rollers 15—15 apply the 75 glue along the vertical edges of the paper.

The transfer rollers 15—15 oscillate backward and forward between the delivery rollers 7—7 and the rollers 21—21 at predetermined times to apply glue to the paper; and to accomplish this I preferably arrange 80 a cam 22' mounted on a stub shaft 23', the former registering with a cam arm 24' secured to the shaft 12 causing the shaft 12 to be rocked each revolution of the cam, causing the transfer disks 15—15 to rock 85 back and forth between the rollers 7—7 and 21—21, transferring the glue from the rollers 7—7 and applying it to the edges of the paper as it passes vertically downward. The stub shaft 23' is rotated by a sprocket 90 wheel and chain, not shown.

It is desirable to have the transfer disks 15—15 rotate with the delivery of the rollers 7—7, and the paper when in contact with either. The shaft 14 is therefore provided 95 with a friction pulley 25 which, when disks 15—15 are in contact with the delivery rollers 7—7 is in contact with the friction-disk 26 keyed to the shaft 6. Said friction-disk 25 in turn is adapted to contact with 100 the friction disk 27 keyed to the shaft 20 carrying the backing rollers 21—21 when the transfer disks 15—15 are in contact with the wrappers.

As a means for feeding the wrappers 105 downwardly at the proper time, I preferably arrange intermediate of the transfer roller a stationary roller 26' journaled in a

suitable support 27'. Opposite this roller are a pair of feed-rollers 28, 28, which are keyed to the shaft 20. These latter rollers are adapted to be oscillated by rocking the 5 rocker-arms 19—19, the shaft 18 upon which these arms are mounted being provided with a cam arm 30 actuated by a cam 29 mounted on the stub-shaft 23', whereby the rollers 28—28 are oscillated forward and backward 10 relative to the stationary roller 26.

The wrappers as they are fed to the pasting mechanism strike the stop fingers 31—31, said fingers being keyed to the transverse shaft 32 supported in the upper end of the 15 frame 16. This shaft is likewise provided with a cam-arm 33 adapted to be actuated by a cam 34 keyed to the shaft 23' serving to retract the fingers 31—31 at predetermined intervals effecting the release of the 20 wrappers the instant the feed rollers 28—28 are moved forward to feed the wrapper downwardly.

The feed rollers 28—28 and the guides 25 21—21 are constantly driven by means of a drive pulley 35 loosely mounted on the shaft 18, said pulley having secured thereto a gear wheel 36 which meshes with a pinion 37 keyed to the shaft 20 to which the said rollers are secured.

30 It will thus be seen that I have constructed a pasting machine which is compact in construction, automatic in operation, and one where the several parts are readily removable for cleaning and repair.

35 I claim:

1. A pasting device comprising a glue-pot, delivery rollers, guide rollers, transfer rollers aligned therebetween, and means for alternately shifting said transfer rollers between the delivery and guide-rollers.

40 2. A pasting device comprising a glue-pot, delivery rollers, guide rollers, transfer rollers aligned therebetween, means for alternately shifting said transfer rollers between the delivery and guide rollers, means for feeding a strip between the guide and transfer rollers, and means shiftable into and out of the path of the strip for regulating its movement.

45 3. A pasting device comprising a glue-pot, delivery rollers arranged above said glue-pot, guide rollers, transfer rollers aligned therebetween, means for alternately shifting said transfer rollers between the delivery and guide-rollers, and means for feeding a strip at intervals downwardly between the guide and transfer-rollers.

50 4. A pasting device comprising a base, brackets extending horizontally therefrom, a glue-pot detachably secured to said brackets, delivery rollers, guide rollers, transfer rollers aligned therebetween, and means for

alternately shifting said transfer rollers between the delivery and guide rollers.

5. A pasting device comprising a base, 65 brackets extending horizontally therefrom, a glue-pot detachably suspended beneath said brackets, delivery rollers carried by said brackets adapted to enter said glue-pot, guide rollers arranged in spaced relation 70 with said delivery rollers, transfer rollers aligned between said delivery and guide rollers, means for alternately shifting said transfer rollers between the delivery and guide rollers, means for feeding a plurality 75 of strips between said guide-rollers and transfer rollers, stops arranged in the path of travel of said strips, and means for shifting said stops out of the path of travel of said plurality of strips at intervals.

6. A pasting device comprising a base, brackets extending horizontally therefrom, a glue-pot detachably suspended beneath said brackets, delivery rollers carried by 80 said brackets adapted to enter said glue-pot, guide-rollers arranged in spaced relation with said delivery rollers, transfer rollers aligned between said delivery and guide rollers, means for alternately shifting transfer rollers between the delivery and guide 85 rollers, means for feeding a plurality of strips between said guide rollers and transfer rollers, stops arranged in the path of travel of said strips, feed rollers arranged 90 between said stops, and means for shifting said stops out of the path of travel of the paper, and engaging said feed rollers with the said paper.

7. A pasting device comprising a glue-pot, delivery rollers rotatably mounted 100 above said glue-pot, guide rollers aligned with said delivery rollers, transfer rollers mounted upon rocker arms aligned between said delivery rollers and guide rollers, means 105 for shifting said rocker-arms whereby the transfer rollers alternately engage said delivery rollers and guide-rollers, a paper feed adapted to deliver a plurality of strips between said guide rollers and transfer rollers, stop fingers arranged in the path of 110 travel of said plurality of strips, feed-rollers arranged between said stop fingers comprising a stationary and movable roller, and means for simultaneously shifting said 115 stop fingers out of the path of travel of the plurality of strips of paper, and shifting the feed rollers into engagement with said plurality of strips of paper, whereby the paper is fed downwardly between the guide and transfer rollers.

In testimony whereof I affix my signature.

EUGENE G. KERLIN.
